US0D1083669S

(12) **United States Design Patent** (10) Patent No.: **US D1,083,669 S**
(45) Date of Patent: ** Jul. 15, 2025

(54) **VEHICLE**

(71) Applicant: **Zoox, Inc.**, Foster City, CA (US)

(72) Inventors: **Timothy David Kentley-Klay**,
Stanford, CA (US); **Nahuel Elias Battaglia**, Stanford, CA (US); **Herman Francisco Delos Santos**, Redwood City, CA (US); **Richard Luke Osellame**, Redwood City, CA (US); **Christopher John Stoffel**, San Carlos, CA (US)

(73) Assignee: **Zoox, Inc.**, Foster City, CA (US)

(**) Term: **15 Years**

(21) Appl. No.: **29/794,640**

(22) Filed: **Jun. 14, 2021**

(57) **CLAIM**

The ornamental design for a vehicle, as shown and described.

DESCRIPTION

FIG. 1 is a front perspective view of a vehicle;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The dashed broken lines depict portions of the vehicle that form no part of the claimed design. The dot-dashed broken lines represent boundaries of the claimed vehicle and form no part of the claimed design.

1 Claim, 7 Drawing Sheets
